UNITED STATES PATENT OFFICE.

ERASTUS E. WINKLEY, OF LYNN, MASSACHUSETTS, ASSIGNOR TO UNITED SHOE MACHINERY CORPORATION, OF PATERSON, NEW JERSEY, A CORPORATION OF NEW JERSEY.

HEEL-BUILDING MACHINE.

Application filed December 20, 1915, Serial No. 67,814. Renewed July 10, 1922. Serial No. 573,917.

To all whom it may concern:

Be it known that I, ERASTUS E. WINKLEY, a citizen of the United States, residing at Lynn, in the county of Essex and State of Massachusetts, have invented certain new and useful Improvements in Heel-Building Machines; and I do hereby declare the following to be a full, clear, and exact description of the invention such as will enable others skilled in the art to which it appertains to make and use the same.

This invention relates to heel machines, and more particularly to such machines for preparing heel blocks for the heel compressing operation by assembling pasted lifts of heel material into a block of the proper contour and subjecting the resultant shaped heel pile to pressure for a sufficient length of time to insure the setting of the paste, although many features of the invention are applicable to machines of widely different characteristics.

It has heretofore been the practice to assemble the pasted heel lifts in a suitable matrix, or former, and then to transfer the pile so produced manually from the former to a pressing machine, in which it is held under pressure while the paste dries and sets. In accordance with this mode of operation it has been found necessary to drive one or more nails through the heel lifts in order to hold them temporarily in their correct assembled relation while the pile is being transferred from the former to the press.

One object of the present invention is to combine the assembling and pressing instrumentalities in a single unitary machine in such a manner and relation that the nailing operation may be eliminated.

Accordingly a feature of the invention comprises the combination with a series of intermittently movable heel block holders or presses, of a heel-former for shaping pasted heel lifts into the proper contour of block and movable to transfer the shaped blocks to the presses. The press structure and heel-former are so associated and operated that the pasted heel pile is delivered directly to the press from the former, and by the movement of the former, the alined heel pile remaining under the control of the former until it has been seized by one of the movable series of presses. The construction of the heel-former, the manner in which it is actuated, preferably in co-oper-

ation with a second heel-former, and the release and withdrawal thereof from the clamped heel block so that a former may constantly be presented in receiving position, all form features of novelty in the combination just defined. A still further feature comprises novel mechanism for ejecting the pressed and dried heel blocks from the presses, operating in such time relation to the moving parts as to successively prepare the presses for the introduction of freshly shaped heel piles at each forward step of the series of presses.

A further object of the invention is to improve the construction and operation of heel presseses of the type referred to in such manner as to provide for speed in operation by reducing to a minimum the weight of the moving parts, and for efficiency through an accurate control of the individual presses. One means to this end is the provision of heel clamps each normally held closed, preferably by a spring, and co-operating clamp opening means that operates independently of the advancing movement of the clamps. After being opened against the opposition of its closing device, each clamp is held open for ejection of the pressed heel block and until it is loaded with a new heel block. A further means by which an efficient and accurate operation is attained is a design of the machine providing for all the operations upon the clamps and the ejection and loading of the heel blocks during the brief periods of rest of the intermittently movable endless series of heel presses.

Other objects of the invention, and the features of construction and operation by which they are attained, will be readily apparent to those skilled in the art from the following description of the preferred embodiment. The invention, in its broader aspects, is not confined to the specific structural details and mode of operation set forth, and the advantages and benefits thereof may be attained by machines differing widely in certain respects from that shown and described. Nor is the invention limited to the conjoint use of all its features, and it will be understood from this specification that it is within the scope of the invention to use some features without others or to combine the various features in a different manner than is described as the preferred combination. Therefore, only such

limitations should be imposed as are indicated in the appended claims.

In this specification the term "heel lift" is used inclusively to designate pieces of material, of whatever nature they may be, that are utilized as the components of the heel being built, and the term "heel block" is used to designate the product obtained by piling the pasted lifts prior to the compressing operation, that is, either the freshly pasted heel pile, which is a "wet" or "green" heel block, or the dry, pressed heel pile ready for the heel compressing operation, in order to distinguish this article from the commercial "heel blank" which is a product of the heel compressor.

The preferred form of the invention is illustrated in the accompanying drawings, in which:

20 Figure 1 is a front elevation of a machine embodying the invention.

Fig. 2 is a front elevation of the main portion of the machine, on a larger scale than Fig. 1;

25 Fig. 3 is a plan view of the parts shown in Fig. 2;

Fig. 4 is an elevation of the left hand end of the machine, showing the sprocket wheels on that end in section;

30 Fig. 5 is an elevation of the right hand end of the machine, showing the sprocket wheels at that end in section;

Fig. 6 is a plan view of the heel former mechanism and two of the beds of the heel 35 block presses;

Fig. 7 is a front elevation of the mechanism shown in Fig. 6;

Fig. 8 is a detail view of the cam mechanism for operating the left hand heel block former slide and heel press operating mechanism;

Fig. 9 is a detail view of the stop cam and its associated lever mechanism; and

40 Fig. 10 is a detail view, in vertical section, of one of the heel-presses.

In the embodiment of the invention illustrated in the drawings the machine is shown as having a frame composed of a vertical front plate 2 and a rear plate 3 (Figs. 4 and 5) which are spaced in parallel, fixed relation by an intermediate box frame 4, suitably secured to the vertical plates. The rear plate 3 and the front plate 2 have their uppermost edges in the same plane, but the 50 front plate extends to the floor and acts as a support for the front of the machine, while the rear plate 3 is supported by a pair of rearwardly extending legs 6 (see Figs. 2 and 3).

60 Power to operate the several mechanisms of the machine is derived from any convenient source and applied to a pulley 10 (Fig. 1), loosely mounted on a driving shaft 11 on which is also mounted a fixed clutch member 12 cooperative with a complementary

clutch member on the pulley 10. The shaft 11 is supported in journals in the frame of the machine, and is provided on its inner end with a worm 14 (Fig. 2) which meshes with and drives a worm wheel 15 secured upon a short transverse shaft 16 carrying, at its rear end, a bevel gear 17 (Fig. 3). The bevel gear 17 meshes with and drives a bevel gear 18, of equal size, secured upon one end of a cam shaft 19 extending parallel to the drive shaft 11 and mounted in bearings in the frame legs 6-6. Also secured on the cross shaft 16 is an interrupted gear 20 (Fig. 2) having a short segment of gear teeth which are adapted to mesh, once in each revolution of the shaft 16, with a complementary interrupted gear 21, which is fixed on a transverse shaft 23 journaled at the left hand ends of the plates 2 and 3. The gear 21 has a plurality of sets of teeth disposed on successive, equal, separated arcs. This mechanism will be recognized as the ordinary Geneva stop motion.

The shaft 23 also carries a pair of spaced sprocket wheels 24, arranged in common vertical planes with a second pair of parallel sprocket wheels 26 which are secured, at the right hand end of the machine, on a transverse shaft 27 (see Fig. 1). The two pairs of sprocket wheels are connected by parallel sprocket chains 28, the upper stretches of the chains running approximately in the horizontal plane of the upper edges of the front and rear frame members 2-3.

The matrices or formers in which the lifts are deposited are mounted at the upper front portion of the frame, upon a forwardly projecting shelf 30 (Figs. 2, 4 and 7) to which is secured a removable base-plate 31 having ways 32 provided for the sliding movement of right and left hand slides 33. Each slide 33 has a horizontal body portion, running in the slide ways 32, and a perpendicular side wall 34. To the top edge of the wall 34 is secured a plate 35 which projects horizontally over and somewhat above table 36 which is secured, by screws 37, to the central portion of the base-plate 31. The former in which the lifts are successively piled, or in which a green heel block may be deposited, comprises two members in the form of arms 39. These arms are pivoted, at their forward ends, on studs 38 depending from the plate 35, and the arms rest upon the table 36. Each of the arms 39 is provided with a perpendicular breast gage surface 40 and one or more side gaging surfaces 41, 42 which latter are formed according to the style and shape of the lateral surface of the heel to be built. As shown in Fig. 6, the breast gages 40 are in a common vertical plane and the rear ends of the arms 39 are provided with gage surfaces 42 which are inclined inwardly and downwardly in conformity to

the pitch of the heel to be produced. The intermediate side gages 41 are also inclined inwardly and downwardly to fit the sides of the heel. With this construction, the matrix 5 or heel-former will effect a transverse or edgewise shifting into alined position of individual heel lifts superposed in the matrix, or will transversely shift the component lifts of a green heel block which may have been 10 built outside of the matrix and then placed therein, and thus properly aline the lifts for the subsequent heel compressing operation.

For the purpose of automatically closing the matrix arms 39 into receiving position 15 (Fig. 6) each arm is provided with a laterally extending cam lug 45. When the slide 33 is moving toward the front of the machine the lugs 45 engage fixed abutments 46 on the top of the base-plate 31 and the assembling table 36 whereby the jaws or arms 39 are swung toward each other, about their pivots 38, to the position shown in Fig. 6, whereupon they are automatically latched together by a spring catch 47 pivoted on one 20 of the jaws and engaging a keeper 48 on the opposite jaw. When the arms are latched together they closely embrace a lug 50, which depends from the plate 35, and this lug acts to centralize the former and the heel-pile held therein. The outward, or opening, movement of the former jaws 39 is limited by stop pins 51 carried by the plate 35. The surface of the table 36 provides a support for the lowermost lift of the heel block.

It is a feature of the present invention 35 that an operative can work to continuously supply heel lifts to a former without having to wait on the operation of the machine to bring a former to receiving position, and for that purpose the two formers are moved 40 alternately to carry to the presses a completed pile of lifts, so that one or the other of them is out in the filling, or lift receiving, position all of the time.

For the foregoing purpose each slide 33 is 45 connected, by a pin 59, to a link 60 (Fig. 3) which extends rearwardly and is connected to the upper end of a cam lever 61 (Fig. 8) which carries a roller 62. The roller 62 of the right hand former slide 33 operates in a 50 groove formed in a cam disk 63 secured on the shaft 19, while the roller 62 of the left hand former operates in a groove formed in a cam disk 64 on the shaft 19 (see Fig. 8).

Both of the formers must be out of the 55 path of movement of the presses during the intermittent advancing movements of the latter. In order to economize in the time of operation the conveyor is moved, at each operation, through the space of two presses, and prior to such movement each of the two formers, after having received a heel-pile, or a series of heel-lifts assembled therein, is retracted to deliver the heel-pile to the corresponding press. Thus two presses are loaded

and two are discharged during each dwell of the conveyor, and then the two formers are brought to their forward positions to permit the filled presses to be moved away, and the two presses from which heels have just been 70 discharged to be brought into cooperative relation with the formers.

After a heel block has been built as described in one of the formers it is carried rearwardly by the former, across the table 75 36, and deposited in a heel block press. Fixed to the chains 28 are a series of press plates 70 each carrying a press structure so that each press is moved by the conveyor, which is formed by the press plates and the endless 80 sprocket chains 28, through a continuous orbit. When traveling in the upper horizontal stretch of the orbit, adjacent the top of the machine, the ends of the press plates 70 slide upon parallel supporting rails 71 which 85 are secured to the upper edges of the front and rear frames 2 and 3. These rails serve the purpose of supporting the upper stretch of the endless conveyor and also insure the proper alinement of the press structure with 90 the matrices.

Integral with each press plate 70, adjacent the rear end thereof, is a depending bracket 72 which supports a heel block receiving bed 73 (Figs. 4 and 5) the surface 95 of which is maintained by the supporting rails 71, while the plates 70 bear thereon, in substantially the same plane as the top of the table 36. The front edges of the bed plates 73 run close to the rear edge of the 100 table 36 (see Fig. 6) so that, when a matrix is shifted across the table 36 the heel block carried therein may easily be placed on the bed plate. It will be understood that the bed plates are intermittently held stationary 105 in heel block receiving position by the Geneva stop mechanism hereinbefore referred to.

After a heel block has been transferred from the table 36 to a registering press bed 110 plate 73 (Figs. 4 and 5) it is then clamped thereon by a platen 74, of suitable form, which is mounted on the lower end of a stem 75 (Fig. 10) which slides vertically 115 through the press plate 70. This stem is automatically pressed downward by an expansion spring 76, mounted upon the reduced upper portion of the stem 75, and is guided in an upper bearing 77 against which the upper end of the spring 76 abuts.

For the purpose of lifting the platen 74 at a predetermined position of the press in its orbit, there is clamped to the upper end of the stem 75 a collar 78, to which is pivoted, at 79, the upper link 80 of a toggle, 120 the lower link 81 of which is pivoted at 82 on the upper side of the press plate 70. When the toggle 80-81 is straightened it operates to lift the platen 74 against the force of the spring 76, and when the toggle 125

80—81 is broken (as in Fig. 10) the spring 76 is permitted to force the platen 74 downward.

The means for breaking the toggles 80, 81, 5 comprise a lever 84 (Fig. 4) loosely pivoted upon a pivot rod 85 which is mounted above the top of the frame in a pair of end brackets 86. The lever 84 cooperates with an arm 83 projecting rearwardly from the lower link 81 of the toggle, and it has a rearwardly extending arm which is connected, at 87, to the upper end of a vertical actuating link 88 (Fig. 8). The link 88 is connected, at its lower end, to a bell crank cam lever 89, 10 which is pivoted upon a pivot rod 90 supported, at its ends, in the frame legs 6—6. This pivot rod also supports the cam levers 61. One arm of the bell crank 89 is provided with a roller 91 which operates in a 15 groove in a cam disk 92 mounted on the cam shaft 19. The cam 92 is so designed that, after a heel block has been shifted by the former into one of the presses alined therewith, the link 88 will descend, rocking the 20 lever 84 in a direction to engage and lift the overhanging arm 83 and thus break the toggle 80—81. As hereinbefore explained this permits the press spring 76 to force the 25 press platen 74 downward on top of the heel block, while held in the former. After the tripping lever 84 has been actuated by its cam 92 to break the toggle the cam 64 operates to return the former to its heel block receiving position on the table 36.

30 Before the former can be moved outwardly by the action of the cam 64, it is necessary to first trip the latch 47 so as to permit the arms or jaws 39 to swing outwardly on their pivots 38 to disengage the heel block, which 35 at this time is firmly clamped in the press. This is accomplished through the means of the former actuating link 60 which, in the initial portion of its outward movement under the action of its cam 64, operates to 40 carry an adjustable lug or striker 95 (Fig. 6), fastened on one side thereof, into engagement with the tail 96 of the latch 47. This swings the latch about its pivot in a direction to unlock the jaws 39 of the former, in advance of any shifting movement 45 of the latter.

This initial motion, to permit the preliminary unlocking of the latch 47, is provided for by slotting the forward end of the link 60 as at 97 (Fig. 4) where it connects with the pin 59, so that the link may have the requisite motion to move the latch 47 before any movement is imparted to the 50 slide 33.

55 After the link 60 has been moved sufficiently by its cam 64 to cause the preliminary opening of the latch 47, its continued forward movement operates to shift the slide 33 outwardly, and the former arms 39 swing outwardly as their surfaces move

around the convexly curved perimeter at the rear portion and sides of a heel block. By the continued forward movement of the slide 33, the pivoted arms 39 of the former are again swung together as their cam surfaces 45 arrive in contact with the fixed abutments 46.

70 It is desirable that, after the slide 33 has retracted the former to its filling position, the operating link 60 thereof be slightly retracted to again take up the lost motion at 97 so that when the slide is to be again shifted inwardly this transfer movement will occur positively without loss of time. This result is obtained by so designing the 75 cams 63 and 64 that at one point, as 98 of each (Fig. 8), their cam grooves are effective, after the cams have turned through the angle necessary to project the slides 33 forwardly, to reverse the motion of the actuating links 60 just sufficiently to take up the play at the slots 97 and then hold the links 60 in this position.

75 In practice, with both right and left hand formers in filling position, the operative will first charge the left hand former with pasted lifts to form a heel block and then in due time, the filled former will automatically move inwardly to deposit the heel block in a press structure. Meanwhile the operative will be filling the right hand former while this is still maintained in its filling position. Before the right hand former is moved inwardly by its cam 63, the left hand former will have been brought forward again by its cam 64, the lever 84 in the meantime having been operated to permit the automatic closing of the press platen 74. When the right hand former is shifted inwardly over an alined press bed plate 73, the platen toggle members will be broken through the agency of another unlocking lever 99 engageable with the registering press arm 83, operated in the manner described for the lever 84, by a cam 100 which is timed to release the platen to the control of its spring just at this time. As soon as the platen 74 has been automatically closed to clamp the heel block to the bed plate 73, the cam 63 operates to move its link 60 forwardly with the consequent operations on the former hereinbefore described.

100 With the cams 63 and 64 so designed and disposed that they will operate to alternately shift first one and then the other of the formers from an outer, or filling, position to an inner, or press loading, position and then to maintain them alternately, and for a period of both of them simultaneously, in their outer positions, it will be seen that 105 the operative may constantly be filling one or the other of the formers.

110 The illustrated form of the invention is such that, while a pair of presses are in charging or loading position in register 115

with the formers, a pair of heel blocks which have previously been formed and loaded into the presses and have passed around the entire orbit will have been brought up to an unloading or ejecting station, in the present case just to the right of the loading station (see Figs. 1 and 2). At the discharging station mechanism is provided to unclamp the blocks in a pair of presses simultaneously and then eject the blocks from the machine. The unclamping mechanism comprises a trip lever 105 (Fig. 5) which is provided with a pair of rigid parallel arms 106 arranged to overhang the toggle-actuating arms 83. The lever 105 is pivoted upon the pivot rod 85, and it has a rearwardly extending arm connected, at 107, to a vertical link 108, to the lower end of which link there is connected a bell-crank cam lever 109, pivoted on the pivot rod 90. The cam lever 109 carries, at the end of its upright arm, a roll 110 which engages a groove in a cam disk 111 mounted on the cam shaft 19. The cam is so designed that during the interval in which a pair of presses are halted at the unloading station, the lever 105 is rocked so that its arms 106 will press downwardly against the arms 83, so that the toggle links 80-81 of the two presses at the unloading station are straightened and lift the respective platens 74 upwardly against the pressure of their springs 76, thus releasing the heel blocks in the presses.

As soon as the heel blocks have been thus released they are ejected from the machine into a forwardly and downwardly inclined discharge chute 115 (Figs. 3 and 5), at the upper front portion of the machine, by means of an ejector comprising a rearwardly extending forked member 117 (Figs. 3 and 4) which is pivoted, at its rear end, on an upright supporting link 118. The ejector is connected to a cam lever 119 which has a roller 120 engaging a groove in a cam disk 121 on the shaft 19. The forward forked end of the ejector 117 is provided with V-shaped faces 122 (Fig. 3) which are arranged to operate in a substantially horizontal plane to engage and eject the pair of heel blocks at the discharging station, when the cam 121 advances the ejector.

The vertical webs 72 of the bed plates 73 are provided with apertures 123 (Fig. 2) through which the ejector ends 122 may move forwardly to engage and eject the heel blocks. While the conveyer is in motion the ejector 117 is held in a retracted position.

The machine is started and stopped by means of a treadle 130 (Figs. 1 to 4) secured upon a treadle shaft 131 which, by reason of a suitably connected torsion spring 132, continuously tends to rock in a direction to render the driving mechanism inop-

erative. On one end of the treadle shaft 131 is secured an upwardly extending arm 133 to which is connected a rearwardly extending horizontal link 134, the opposite end of which is connected to a lever 135 (Figs. 4 and 9), mounted on the pivot shaft 90, and carrying, on its upwardly extending arm, a roller 136 adapted to interlock with a stop plate 137 secured on the cam shaft 19. The stop-plate is formed with a plurality of shoulders 138 for engagement with the roller 136. On the other end of the shaft 131 is an upwardly extending arm 133', connected to one end of a link 134' (Fig. 4) the other end of which is connected, at 140, to a lever 141. The lever is pivoted on a stud 142 mounted in a foot bearing 143 provided for the outer end of the shaft 11. At the upper end of the lever 141 a link 144 connects the lever to one end of a concaved clutch shoe 145, pivoted at 146 upon the foot bearing 143 (see dotted lines Fig. 4). The clutch shoe 145 is adapted to engage with a pin 147 which is secured to the clutch member 12, so as to interrupt the rotation of the latter and thus disconnect the shaft 11 from driving relation with the pulley 10. When the operative desires to start the machine, he depresses the foot treadle 130, which swings the arm 133' forward, against the torsional effect of the spring 132 on the treadle shaft 131, and shifts the link 134' forward to rock the lever 141 and withdraw the clutch shoe 145 from engagement with the clutch pin 147.

The clutch member 12 is thus permitted to become operatively engaged with its complementary member, and the shaft 11 is turned. The operative may either continue to hold the foot treadle 130 down, or may lock it in its lower position by a lock arm 150, pivoted at 151, which is adapted to be swung horizontally over the depressed end of the treadle 130 and thus hold the latter in this position. When the operative desires to interrupt the operation of the machine the locking arm 150 may be turned horizontally with the foot, so as to release the treadle 130. As soon thereafter as the roller 136 encounters one of the depressions in the stop-plate 137, the spring 132 is permitted to rock the shaft 131 in a direction to throw out the drive-clutch, and the cam-shaft and other parts are then brought to rest, in the proper position, by the engagement with the roller 136 of the stop-shoulder 138.

This invention is not limited to the embodiment thereof hereinbefore described and illustrated in the accompanying drawings, but it may be embodied in various other forms within the scope of the following claims.

What is claimed as new, is:—

1. A machine of the character described, having in combination, a traveling carrier,

devices, for operating upon heel blocks, sustained by said carrier, means, constantly presented in receiving position, on which lifts are assembled into heel blocks and operative to transfer each block as assembled to one of said devices on the carrier, and means to operate the carrier to present new devices to said means for each operation thereof.

10 2. A machine of the character described, having in combination, a traveling carrier, devices sustained by the carrier for applying pressure to green heel blocks, and block forming means, for shaping the blocks from 15 superposed heel lifts, alternately operative to transfer the blocks to said pressure applying devices.

3. A heel-building machine having, in combination, a series of intermittently and 20 bodily movable heel block presses, a heel former arranged and adapted to shape piled heel lifts into the proper contour of block by engagement with the lateral surfaces of 25 the lifts including the breasts thereof, and means for actuating the former to transfer the shaped heel blocks to the presses.

4. A heel-building machine having, in combination, a plurality of shiftable heel block formers, a series of traveling heel 30 block presses to which the blocks are transferred by said formers, means to move the formers toward and from the presses, and means to automatically close the presses 35 upon the blocks in the formers before the withdrawal of the formers from the presses.

5. A heel-building machine having, in combination, a series of automatically opening and closing presses for receiving and holding heel blocks under pressure, and a heel 40 matrix having side and breast gages for shaping piled, pasted heel lifts into heel blocks of given form, said matrix being movable to transfer the shaped blocks to said presses, hold the blocks thereat until the 45 presses close, and then be withdrawn leaving the blocks in the presses.

6. A heel-building machine having, in combination, an endless series of heel block 50 presses operative to clamp and carry green heel blocks for a period sufficient to permit substantial setting of the paste, and then automatically release the blocks, means comprising a heel-former having side and breast 55 gages for shaping freshly pasted lifts into heel blocks of given form, and means to operate said shaping means to transfer the shaped blocks to the presses, said shaping means being constructed to permit withdrawal from the blocks when they are 60 clamped by the presses.

7. A heel-building machine having, in combination, a series of heel block presses 65 intermittently movable through a predetermined orbit, means for automatically opening and closing the presses at prede-

termined stations in their orbit to permit the insertion and discharge of heel blocks, and a heel matrix having side and breast gages for shaping freshly pasted heel lifts into heel blocks of predetermined contour, 70 operative to transfer the shaped block to an open press and deposit it therein.

8. A heel-building machine having, in combination, a plurality of traveling presses, means for intermittently advancing the 75 presses, a slide carrying a heel block former, said former comprising movable gage arms or jaws latched in closed position, means for actuating the slide to deposit a heel block in a press, and means for automatically unlatching the members of the former after it has deposited a blank in a press, thereby 80 permitting opening of the jaws and the withdrawal of the former from the deposited blank.

9. A heel-building machine having, in combination, a plurality of traveling presses, means for intermittently advancing the 90 presses, a slide carrying a heel block former, said former comprising movable gage arms or jaws latched in closed position, means for actuating the slide to deposit a heel block in a press, means for automatically unlatching the members of the former after it has deposited a blank in a press, thereby permitting opening of the jaws and the withdrawal of the former from the deposited blank, and means for automatically relatching the jaws 95 of the former as the slide withdraws from the press.

10. A heel-building machine having, in combination, a traveling, automatic heel block press, means for imparting movement to the press, means for shaping freshly pasted heel blocks movable to carry said blocks into position to be clamped by the press, and means outside the press structure operating after a time for engaging and automatically ejecting the pressed blocks 100 from the press.

11. A heel-building machine having, in combination, an intermittently movable, endless train of relatively articulated heel block presses, means for shaping green heel blocks and holding them in position to be clamped in presses registering with said means during intervals of rest of the press train, and means operative during the same 115 interval to remove previously pressed blocks from other presses.

12. A heel-building machine having, in combination, a plurality of formers for shaping superposed heel lifts into a heel block of given contour, an endless carrier, with a plurality of presses, movable to intermittently and progressively present to all of said formers a corresponding number of the presses, and means to actuate the formers to place their heel blocks in the 125 presses.

13. A heel-building machine having, in combination, an endless series of heel block presses arranged for simultaneous, intermittent travel, and means for loading a plurality of said presses with heel blocks during an interval of rest.
14. A heel-building machine having, in combination, an intermittently movable endless series of heel-block presses, a heel former in which a heel-block may be assembled, by superposing lifts therein constructed and arranged to engage the breast and sides of the lifts and shape them to a predetermined contour of heel block, and means for moving the former to bring the shaped heel block therein into position within one of the presses during a dwell in the intermittent movement of the latter.
15. A heel-building machine, having, in combination, a heel block press comprising a series of bed plates successively movable to heel receiving position and a clamping device movable toward and from each bed plate; a heel former, constructed to surround lifts in a pile with their breast edges alined and having yielding side members to provide for withdrawal from the heel, movable to successively load said bed plates, while in heel receiving position, with assembled heels; and means for automatically operating said clamping devices as the heels are delivered to the bed plates by the former and then withdrawing the heel-former from the clamped heels.
16. In a heel-making machine, a series of heel-holders, each holder having means for clamping a heel thereon, means to move said holders successively into a heel-receiving position, a heel-former including an end wall to engage the breast of a heel therein and aline the component lifts thereof, and means to move said former to deliver the alined lifts onto each holder when in said receiving position.
17. In a heel-making machine, a series of heel-holders, each holder having means for clamping a heel thereon, means to move said holders successively into a heel-receiving position, and a heel-former constructed to engage both the breast and the lateral surface of a heel therein to aline the component lifts thereof reciprocally movable to and from said position to deliver the alined lifts to said holders, successively, when in said position.
18. In a heel-making machine, a series of heel-holders, each holder having a heel-receiving seat and means for clamping a heel thereon, means to move said holders in a predetermined path, successively into a heel-receiving position in which the seat thereof is held horizontally, and a heel-former constructed to aline lifts placed therein into heel form by engagement with their breasts, sides and backs movable transversely of said path to deliver the alined lifts onto each holder when in said receiving position.
19. In a heel-making machine, a series of heel-holders, each holder having a heel-receiving seat and means for clamping a heel thereon, means to move said holders in a predetermined path, into a heel-receiving position, successively, in which the seat thereof is held horizontally, and a heel-former comprising gaging members for engaging the breasts of the heel lifts therein to vertically aline said breasts one above the other horizontally reciprocal transversely of said path to deliver alined lifts onto each holder when in said receiving position.
20. In a heel-making machine, a series of heel-holders, successively movable into a heel-receiving position, a heel matrix having gaging means at its breast end, sides and back for receiving and alining the component lifts of a heel placed therein movable to deliver the alined lifts onto said holders when in said position, a clamping device for each holder, and automatic means for moving each clamping device into clamping position when the alined lifts are delivered onto its corresponding holder.
21. In a heel-building machine, a heel-clamp having a horizontally disposed member, a heel-form movable from a filling position to a delivering position directly over said member and having a heel-receiving recess therein open at top and bottom, means on said form arranged to engage the breast side and the back side of a heel in said recess, means to actuate the other member of the clamp to clamp a heel while held by said form in said delivering position, and means permitting the forming means at the rear side of the form to yield to permit the form to be withdrawn from the heel, while held by the clamp.
22. An automatic heel block pressing machine having, in combination, an endless series of heel block presses arranged to be moved simultaneously in intermittent steps, means for loading a press of the series, and means for concurrently unloading the next following press.
23. A press having, in combination, a plurality of clamps arranged in an endless series, each clamp being provided with a spring by which it is closed; means for moving the series of clamps in a definite path successively past a given point; a device engageable with each clamp at said point; and additional means to move said device transversely of the path of motion of the clamp to open the clamp against the opposition of said spring.
24. A press having, in combination, a plurality of clamps arranged in an endless series, each clamp being provided with a spring by which it is closed; means cooperative with the clamps successively to open

them against the opposition of said springs; and mechanism for moving the clamps successively into and out of cooperative relation with said means and for actuating said means independently of the advancing movement of the clamps.

25. A press having, in combination, a plurality of clamps arranged in an endless series; means for moving the clamps successively past a loading station; expansion springs acting normally to hold the clamps closed; clamp-controlling devices operating to open the clamps by a compression of said springs on approaching said loading station, said clamps remaining open until they are loaded; and means movable across the line of travel of the clamps for ejecting the work before the loading station is reached.

26. A heel making machine having, in combination, an endless series of movable heel presses each comprising an upper member and a lower member between which heel stock is clamped and held; means normally tending to actuate said heel presses into clamping relation; means for intermittently actuating said series of heel presses; means operating during periods of rest of said heel presses for opening a heel press; and means acting while the heel press is open to introduce a heel stock therein.

27. A heel making machine having, in combination, an endless series of heel presses intermittently movable and each comprising relatively movable members between which a heel block may be introduced in position to have its opposite faces engaged thereby; means movable in substantially the plane of the faces of the clamps for removing the pressed heel blocks therefrom; a heel form for shaping said heel blocks; and means for actuating said form to supply new heel blocks to the empty presses.

28. A heel making machine having, in combination, an endless series of heel presses, each comprising relatively movable members for engaging the opposite faces of a heel block disposed therein; means normally tending to actuate said members into clamping relation; means for advancing said heel presses in steps; and means operable during periods of rest of said advancing means for opening the heel presses successively.

29. A heel making machine having, in combination, a series of heel presses intermittently movable through an unloading station; means tending to hold the heel presses in clamping relation; and means disposed at said station and operable during periods of rest of said heel presses for opening the heel presses as they are successively presented thereto.

30. A heel making machine having, in combination, an endless series of heel presses comprising pairs of clamping plates, a toggle

connected to each press through which the opening and closing of the press is controlled, means for advancing said series of presses intermittently through a fixed orbit, and means for operating said toggle during periods of rest of the press structure to open and close the presses.

31. A heel making machine having, in combination, an endless series of heel presses comprising pairs of clamping plates, a toggle connected to each press through which the opening and closing of the press is controlled, means for advancing said series of presses intermittently through a fixed orbit, and means having a fixed relation to the orbit of the movable press structure for operating said toggle successively.

32. A heel making machine having, in combination, an endless series of heel presses comprising pairs of clamping plates, a toggle connected to each press through which the opening and closing of the press is controlled, means for advancing said series of presses intermittently through a fixed orbit, toggle straightening means at one station in the orbit, and toggle breaking means at another station in the orbit whereby each heel is subjected to pressure during the travel from one station to the other.

33. A heel machine having, in combination, a series of intermittently and bodily moving heel block presses, a heel-former arranged and adapted to shape piled heel lifts in the proper contour of block comprising a pair of jaws, each provided with gages for the rear lateral surface and the breast end of the heel, said jaws being relatively movable about pivots at one end thereof, and means for actuating the former to transfer the shaped heel blocks to the presses.

34. A heel machine having, in combination, a series of intermittently and bodily moving heel block presses; a heel-former arranged and adapted to shape piled heel lifts into the proper contour of block comprising a pair of jaws, said jaws being pivoted at one end to permit an opening and closing movement, and each being provided with a breast gage at the pivoted end thereof and a rear lateral surface gage at the open end; and means for actuating the former to transfer the shaped heel blocks to the presses.

35. A heel machine having, in combination, a plurality of travelling presses, means for intermittently advancing the presses, a heel-former comprising side jaws pivotally mounted at one end and open at the other, each jaw having side and breast gages for alining lifts deposited therebetween to a shaped heel pile, means for advancing said former to deposit a shaped heel in a press, and means for maintaining said jaws in closed relation during said advance con-

structed and arranged to permit them to open about their pivoted ends to withdraw from the heel after it has been deposited.

36. A heel machine having, in combination, an endless series of heel clamps, each comprising relatively movable members for engaging the opposite faces of superposed pieces of heel stock; means continually tending to actuate said members into clamping relation; means for advancing said heel clamps in steps; means operable during periods of rest of said advancing means for opening the members of the heel clamps; and means for delivering heel stock to said 10 clamps while the members thereof are open, and for thereafter permitting said members to close upon the stock delivered thereto.

37. A heel machine having, in combination, an endless series of heel clamps, each comprising relatively movable members for engaging the opposite faces of superposed pieces of heel stock; means continually tending to actuate said members into clamping relation; means for advancing said heel 20 clamps in steps; and means operable during periods of rest of said advancing means for automatically opening said members to receive the heel stock and then permitting said members to close on the heel stock disposed 25 therebetween.

38. A heel press having, in combination, a movable carrier; means for intermittently moving said carrier in steps; an endless series of heel clamps mounted on said carrier comprising members for engaging the opposite faces of heel stock disposed therein; and means operating upon one of said members of each clamp during periods of rest of said carrier for opening and closing said 40 clamps.

39. A heel press having, in combination, a movable carrier; means for intermittently moving said carrier in steps; an endless series of heel clamps mounted on said carrier comprising members for engaging the opposite faces of heel stock disposed therein; a spring on each clamp arranged to continually urge one of its members toward the other to clamp the heel stock; and means 45 operating during periods of rest of said carrier for withdrawing a member against the force of said spring to open the clamp, and thereafter releasing said member to again clamp the heel stock.

40. A heel machine having, in combination, a plurality of heel clamping presses mounted on a movable carrier, means for imparting an intermittent movement to said carrier to advance the heel presses, and a device automatically presented in receiving position on which lifts are assembled into heel form and operative to transfer each heel as assembled to one of said presses on the carrier as the movement thereof presents said presses to said device.

41. A heel machine having, in combination, a device for facilitating the assembly of a plurality of lifts into heel form, an endless series of movable heel presses, each comprising an upper member and a lower member between which heels are clamped and held, means for moving said presses simultaneously to cause them to successively travel past said device, said device being bodily movable to transfer each heel as assembled to one of the presses, and means for automatically returning said device to heel building position after each transfer of a heel to a press.

42. A heel pressing machine having, in combination, an endless series of heel presses, each comprising a pair of clamps, arranged to be advanced simultaneously in intermittent steps; means for successively closing said clamps, upon heels positioned therebetween, at one station in the orbit of the presses; means for successively opening said clamps at another station in said orbit; and reciprocating means operating after the clamps are opened for accomplishing an 90 ejection of the pressed heels in succession.

43. A heel pressing machine having, in combination, an endless series of heel presses comprising pairs of clamping plates, means for advancing said presses in intermittent 95 steps through a clamping and an unclamping station, a power operated actuator at the clamping station for acting on one of the clamping plates of each press in succession to close the presses on heels positioned between said plates, and another power operated actuator at the unclamping station for acting a second time on said clamping plate to successively open the presses.

44. A heel pressing machine having, in combination, an endless series of heel presses comprising pairs of clamping plates, means for advancing said presses in intermittent steps through a clamping and an unclamping station, a power operated actuator at the clamping station for successively acting on one of the clamping plates of each press to close the presses on heels positioned between said plates another power operated actuator 110 at the unclamping station for acting a second time on said clamping plate to successively open the presses, and means for thereafter forcibly ejecting the pressed heels from the conveyor.

45. A heel pressing machine having, in combination, an endless chain conveyor, spaced sprockets for supporting said conveyor, means for rotating said sprockets intermittently to advance the conveyor through a plurality of stations, a plurality of heel presses comprising pairs of clamping plates mounted on said conveyor and advanced thereby step by step through said stations including a clamping station and an unclamping station, means operating during 125 130

the period of rest at the clamping station for successively closing the clamping plates of each press on heels positioned therebetween, and means operating during the period of 5 rest at the unclamping station for successively opening the clamping plates of each press to permit the pressed heels to be removed from the conveyor.

46. A heel machine having, in combination, means for holding a heel under pressure, means for advancing said holding means through an ejecting station and a loading station, and means for releasing the pressure from the heel and effecting its ejection including a device carried by the holding means for retaining said holding means in released position during its movement through said loading station.

47. A heel machine having, in combination, a normally closed heel-clamping press, means for advancing the press through an ejecting station and a loading station, and means for opening the press to permit ejection of the heel, said means operating automatically to retain the press open while the pressed heel is ejected and until it has been loaded with a new heel.

48. A heel machine having, in combination, an endless series of heel-clamping presses, mechanism for advancing said presses step-by-step in a fixed orbit, means having a fixed relation to the orbit of the

movable press structure for opening each press as it reaches said means, and a device carried by the press for retaining the press 35 open as it advances beyond the control of said means.

49. A heel machine having, in combination, an endless series of heel-clamping presses, mechanism for advancing said 40 presses step-by-step in a fixed orbit, means having a fixed relation to the orbit of the movable press structure for opening each press as it reaches said means, a device carried by the press for retaining the press 45 open as it advances beyond the control of said means, and means co-operating with said device for closing the press on a new heel loaded therein.

50. A heel machine having, in combination, an endless series of heel-clamping presses each provided with a spring through which they are maintained closed upon a heel therein; mechanism for advancing said presses step-by-step in a fixed orbit; means 55 operating successively on each press, as it reaches a certain station in its travel, for opening the press by compressing said spring; and a device for holding said spring under compression after the press has advanced beyond said press opening means and until it has been loaded with a new heel.

ERASTUS E. WINKLEY.
